(57) **CLAIM**

The ornamental design for a lavatory handle assembly, as shown and described.

DESCRIPTION

FIG. 1 is a perspective view of a lavatory handle assembly, shown from the exterior side, showing our new design;

FIG. 2 is a perspective view of the lavatory handle, assembly, shown from the interior side;

FIG. 3 is a front view of the exterior side thereof;

FIG. 4 is a top view thereof;

FIG. 5 is a right side view thereof;

FIG. 6 is a left side view thereof;

FIG. 7 is a rear view thereof;

FIG. 8 is a front view thereof; and,

FIG. 9 is a bottom view thereof.

The broken line shown in the figure drawings is included for illustrative purposes only and forms no part of the claimed design.
